UNITED STATES PATENT OFFICE

LOUIS PLATT, OF NEW YORK, N. Y., ASSIGNOR TO PLATT HAT MACHINE CORPORATION,
A CORPORATION OF NEW YORK

HAT-FINISHING MACHINE

Application filed December 8, 1927. Serial No. 238,493.

This invention relates to the manufacture of felt hats and in particular to the finishing of such hats by the several operations of blocking, pouncing, brushing, etc. More specifically, the invention is concerned with a machine provided with instrumentalities by which these various finishing operations may be successively performed at a high rate of production and with a minimum of attention 10 on the part of the operator.

In the finishing of felt hats as now carried on, the different operations are performed manually on the felt blanks, or else machines are used which require constant attention on 15 the part of the operator. The hat blanks of rough felt of generally conical shape are first blocked to give the blank its proper final form and for this purpose the felt is steamed to render it pliable and easily worked, then the 20 blank is pulled over a block or form having the inside shape of the finished hat, and an outer form or block is placed in position over the hat. The placing of the blank on the block is done by an operator who grasps the edges 25 of the blank and exerts considerable muscular effort in forcing the blank into tight contact with the block. As the force required for this purpose cannot be applied evenly all around the edge of the blank, it frequently 30 happens that the blank is strained or stretched and in some instances the edges may be torn. The blocks are heated so as to drive off the moisture and press the hat to shape, and this 35 drying operation consumes a considerable period of time. As a consequence, the blocking operation is necessarily slow and laborious and it is difficult by present means for an operator to produce hats of highest quality.

After the blocking operation the next treatment given the hats is pouncing, which involves grinding off the surface of the felt so that the felt may be of uniform thickness. The rough blanks are frequently of uneven thickness and the surface may not be uniform, 45 so that pouncing is a necessary operation. Pouncing is normally carried on by placing the blank on a suitable form and rotating the latter while the workman operates on the surface of the felt with an abrasive tool. This 50 treatment also consumes a great deal of time,

so that the labor charge is relatively high, and it frequently results in defective products because the workman has to determine by his eye the extent to which the hat must be ground. Sometimes the grinding may result 55 in holes being ground in the felt, and in that event the hat must be discarded. Following the pouncing operation, the hat is finished by brushing, buffing, and various other operations are performed on it to raise the nap of 60 the felt and give the felt surface the desired lustre. These operations are also manually performed and with present labor costs add considerably to the cost of the finished article. 65

To overcome the difficulties involved in the use of manual labor for these finishing operations, and also to reduce the cost of the finishing treatment, and to raise the quality of the hats so produced, I have devised a machine 70 which includes instrumentalities by which these various operations can be carried out successively so that a hat blank may be placed in the machine and without removal therefrom acted on successively by blocking, 75 pouncing, brushing, and other devices. This machine is largely automatic in operation and treats the blanks with complete uniformity so that damage to the felt is avoided and articles of high excellence produced. The machine is 80 so arranged that a single operator may supervise a number of such machines, thus reducing labor charges to a great extent.

In the new machine there is provided a pair of cooperating blocks suitably heated 85 and movable by power into operative relation. The blank, previously steamed, is placed over one of these blocks and the edges of the blank are introduced between the jaws of a multiplicity of gripping devices, arranged in a 90 series around the edge of the block. These devices are so arranged that the operator with a single movement can cause all the gripping jaws to engage the edges of the blank and to pull the blank tightly upon the block. The 95 blank is thus forced on the block without unequal strains being placed on the felt, and the time involved in this part of the blocking operation is reduced to a minimum. The operator now starts other mechanism which 100

causes the second block to be fitted over the blank in position on the first. These blocks are suitably shaped to press the hat to desired form.

5 While the pressing and drying operations are going on, the operator may place other blanks in similar machines by the same operations and, after a number of machines have been started, he returns to the first and by a simple manipulation of the mechanism causes 10 the blocks to separate, while the blank is retained on the one on which it was originally disposed. The pouncing mechanism is now brought into operation and for this purpose 15 the block carrying the blank is caused to rotate and a pouncing device moved to effective position. This device is arranged to grind off the surface of the felt evenly so that the felt has a uniform thickness. Following the 20 pouncing operation, other devices are brought successively into operation, and these devices may include means for brushing the felt, means for buffing the felt, and mechanisms for performing various other operations 25 incident to finishing the hat. All of these devices require no attention on the part of the operator, except bringing them successively into action, and the element of skill is thus eliminated so that an operator of little 30 training may use this machine to produce hats of the highest grade.

For a better understanding of the invention, reference may be had to the accompanying drawings, in which

35 Fig. 1 is a view of the machine in vertical elevation with certain parts shown in section,

Fig. 2 is a sectional view on the line 2—2 of Fig. 1,

40 Fig. 3 is a vertical sectional view of the lower block showing the pouncing device in operation, and

Fig. 4 is a view similar to Fig. 3, but showing a modification.

45 In the drawings the machine is illustrated as including a support 10 of any suitable form, here illustrated as a table which includes legs 11 and a bed plate 12. Mounted in suitable bearings below the bed plate and 50 extending therethrough is a hollow shaft 13 having a bevel gear 14 near its lower end which meshes with a bevel pinion 15 on the shaft of a driving motor 16 mounted at any convenient point, as, for example, on a bracket 55 17 secured to the legs 11. The table 12 has a central opening 18 through which the shaft passes and the upper end of the shaft is journaled in a bracket 19 depending from the under surface of the table and attached there- 60 to at either side of the opening 18. This bracket is generally of U-shape and between its legs extends a two-part lever 20 straddling the shaft 13 and pivotally mounted at one end on a pin 21 in a bracket 22 depending 65 from the under surface of the table at one

side of the opening. The other ends of the lever are connected to a rod 23 which is provided at its lower end with a block 24 having teeth along one edge which may be engaged with similar teeth in a standard 25 attached to the floor. The block 24 is provided with a treadle 26 and by depression of the treadle, the lever 20 may be swung on its pivot to different positions relative to the under surface of the table.

70 Mounted on the upper end of the shaft 13 above the top of the table is an inner block or form 27 having the shape of the interior of the hat to be produced. This block is preferably of metal, such as aluminum or the like, and inside it is a heating element 28, which is here illustrated as an electric resistance mounted on a hollow rod 29 which projects through the interior of the hollow shaft 13, the resistance unit being supplied with current through cables 30 extending through the rod 29.

75 Disposed beneath the block 27 on the shaft 13 is a collar 31 fixed on the shaft. Below this fixed collar is a collar 32 slidable on the shaft but rotatable thereby, this collar carrying a plurality of links 33 pivotally mounted in the periphery thereof. Each link 33 is connected to an arm 34 which terminates in a gripping jaw 35. Pivotally mounted on the arm 34 at 36 is another gripping member 37 terminating in a jaw 38 which coacts with the jaw 35. The member 37 has a tail 39 which rests beneath the under surface of the collar 31. A spring 40 attached to the under surface of the base of block 27 at one end is attached at the other end to the gripping member 37 and another spring 42 is attached at one end to the block 27 at a point near the shaft 13 and at its other end is attached to the member 37 at a distance from the pivot 36. The collar 32 has an extension 43 beneath, which is provided with a circumferential channel 44; and a pair of links 45 attached to the two parts of the lever 20 midway of its ends are provided with pins at their free ends, which enter the channel 44 on opposite sides.

80 The gripping jaws 35 and 38 have faces of considerable extent, as, for example, these faces may be 1" x 2", and each gripping member 38 is provided with a tooth 46 lying below the gripping surface.

85 With this arrangement and with the parts in the position shown in Fig. 1, the conical felt blank 47 is placed by the operator in the position illustrated and with its edges lying between the open gripping jaws 35 and 38. In order that the blank may be held firmly in position until it is seized by the gripping jaws, the edges of the blank are engaged on the spikes 46. There are a number of gripping devices disposed about the periphery of the block, preferably six, so 90 that the blank will be grasped at a plurality 95

of points which are relatively closely spaced. After the hat blank has been placed in position, the operator depresses the treadle 26, causing the collar 32 to be pulled downwardly. This movement is transmitted through the links 33, causing the gripping members 34 to swing on their pivots 36, so that the gripping surfaces 35 and 38 are brought into cooperating relation. This action takes place shortly after the commencement of the depression of the treadle and further downward movement of the treadle causes the collar 32 to draw both gripping devices downward to the position illustrated in Fig. 3. The pulling action of the gripping devices causes the hat blank to be drawn tightly over the top of the block 27, and in their lowermost position the grippers lie below the flat peripheral rim 48 of the block. In such downward movement the jaw 38 bears continuously against the edge of the member 48, the latter having a depending flange 41 providing an abutment for the jaw when the latter is in its lowermost position. When the treadle is released, the springs 40 and 42 raise the parts to their original position, the jaws opening as shown in Fig. 1.

After the hat blank has been drawn over the block 27 in the manner described, an outer block 49 is moved to cooperating relation with the inner block. The block 49 is mounted on a cross-head 50 provided with flanged slides 51 movable vertically on guide-ways 52 supported on standards 52' which extend upwardly from the bed 12 of the table. The block is supported on springs 53 from the under surface of the cross-head, so that the block has a certain freedom of movement with reference to its support. The block is made of metal and carries a heating device, which may conveniently take the form of heating coils 54 wound around the outside of the block. The cross-head is mounted on the lower end of a shaft 55, the end of the shaft being squared, as indicated at 56, and projecting through a boss on the cross-head and held in place by a nut 58 on its lower end. The upper end of the shaft 55 is threaded and the threaded end projects through a central bore in a gear 58, the inner face of which bore is also provided with a thread. The gear 58 rests on a row of balls 59 lying between the under surface of the gear and the upper surface of a top plate 60 extending between and supported on the standards 52'. The gear has a tubular extension 61 passing through a central opening in the plate 60 and at its lower end this extension has a collar 62 between which and the under surface of the top plate is another row of balls 63. With this arrangement the gear may rotate freely and dependent on its direction of rotation, the screw shaft 58 is raised or lowered and with it the cross-head

50. A pinion 64 attached to the shaft of a motor 65 mounted on the top plate 60 meshes with the gear 58, whereby the motor may raise and lower the cross-head under control of the operator. The motor is controlled by means of switches 66 and 67, mounted on standards 52'. The switch 66 is disposed a considerable distance from the top of the standards while the switch 67 is placed close to the standards. Each of the slides 51 is provided with a trip arm 68 and the arrangement is such that when the operator wishes the block lowered, he sets the switch 67 to proper position, causing the motor 65 to rotate the gear 58 in a suitable manner to lower the cross-head and block. When the cross-head has moved down to the desired lower position, one of the trip arms 68 will engage the switch 66 and move it to the off position, thereby stopping the motor automatically. In a similar manner the switch 67 controls the upward movement of the cross-head and block, the operator setting the switch to start the motor and the switch being moved to off position at the upper limit of travel of the cross-head by trip arm 68 engaging the switch lever. The springs 53 permit variations in the block used and the setting of these blocks, without requiring that the travel of the cross-head be exactly adjusted.

After the hat blank has been drawn on the lower block and the upper block lowered to cooperative position, the parts are allowed to remain in this position until the hat has been pressed and all the moisture driven off by the heating elements. During this period the operator may attend to other machines of this same type. After the hat has been blocked, the motor 65 is started to raise the cross-head and upper block clear of the blank, and the machine is now ready for the remaining operations. The first of these operations is pouncing and for this purpose there is employed a slide 69 mounted between suitable guides 70 and movable toward and away from the axis of rotation of the shaft 13. The slide 69 is normally forced toward the axis of the shaft 13 by means of a spring 71 connected to one of the standards 52' and to an extending arm 72 at the back of the slide. Any suitable means (not shown) are provided for maintaining the slide in its inoperative position illustrated in Fig. 1, these means being releasable so that the slide can be moved by the spring toward the block. The slide has a curvature on its forward face 73 corresponding closely to the curvature of the outer surface of the block 27 and different slides will be used for different types of hats. The slide has a channel (not shown) formed in its curved face into which a strip of abrasive material 74 may be readily inserted, the channel permitting the abrasive strip to be readily removed and replaced, while at the same time

95

100

105

110

115

120

125

130

holding the strip firmly against movement in the pouncing operation.

As the block 27 is normally of oval cross-section, means are provided for giving the slide a movement toward and away from the axis of the shaft 13 as the block is rotated in order that the abrasive material may act on the hat with uniform pressure. For this purpose a cam ring 75 is mounted by means of 5 arms 76 on the collar 31, the ring having an oval configuration corresponding exactly to the oval cross-section of the block. The slide 69 is provided with a wheel 77 which is positioned so as to bear against the surface of the 10 cam ring when the slide is in operative position, the spring 71 holding the wheel firmly against the surface 75. When the pouncing operation is to be carried on, the operator first causes the blocks to be separated 15 and then, by means of a switch 78 disposed at any convenient place on the machine, starts the motor 16. This causes the rotation of the block 27 with the hat upon it. The locking means for the slide 69 are then released and 20 the slide is moved toward the axis of the shaft 13 until it occupies the position shown in Fig. 3. The abrasive surface of the slide now contacts with the surface of the felt and the 25 grinding operation begins. The cam ring 30 and wheel 77 cause the slide to be moved toward and away from the axis of the shaft so that the grinding surface will always bear a fixed relation to the surface of the block, thus insuring that the grinding is carried on 35 evenly throughout the surface of the blank and permitting the felt to be ground to the desired thickness. This pouncing operation requires no attention on the part of the operator and after he has placed the parts in 40 active position for this purpose he may give his attention elsewhere until the pouncing operation is completed.

When the pouncing operation has been finished various other operations may be performed on the blank, such for instance as 45 buffing the surface of the blank with a felt-covered tool. For this purpose the slide 79, disposed at one side of the slide 69 on the bed of the machine may be employed, this slide 50 having a curved face similar to the face 73, on which face is mounted a layer 80 of buffing material. A similar slide 81 disposed at a 55 distance to the slide 69 may also be provided, this slide carrying a brush 82 in place of the abrasive or buffing material. The slides 69, 79, and 81 are of the same general construction, each of these slides having a curved face corresponding to the contour of a block and being provided with wheels similar to 60 the wheel 77 bearing against the cam ring 75, whereby the slides may move in and out in correspondence with the rotation of the oval block.

Instead of using a stationary brush grinding 65 surface or the like, I may use a rotating

member for this purpose, as shown in Fig. 4. In this construction a slide 83 similar to slides 69, etc., is employed but mounted on the slide on a vertical shaft 85 is a rotational brush 86 grinding roll or the like, the outer surface of which conforms to the outer surface of the block 27. This tool may be driven by means of a pulley 87 and belt 88 from any convenient source of power, and performs various operations, depending on the character of the surface with which it is provided.

In order that the gripping devices may be employed with blocks of different construction, the arrangement illustrated in Fig. 4 70 may be utilized. In this construction the links 34 are made in two parts which partially overlap and are connected by means of a slot and pin construction, generally designated 89. The two parts of the links may be moved relative to each other and set in different positions of adjustment, depending on the shape 75 of the block. The gripping member 37 is provided with a tail 39 of considerable length, so that regardless of where the pivot 36 is placed in each instance, a portion of the tail 90 39 will engage the under surface of the collar 31. The construction is otherwise the same as that previously described.

I claim:

1. A machine for finishing hats which comprises the combination of a block adapted to receive a hat blank, a plurality of gripping means associated with the block operable to grasp the edges of the blank and movable in a direction parallel to the axis of said block 95 to draw the blank into tight engagement with the block, a second block adapted to cooperate with the first, and power-driven means for effecting relative movement of the block into and out of cooperating relation.

2. A machine for finishing hats which comprises the combination of a block adapted to receive a hat blank, a plurality of pairs of gripping jaws associated with the block and distributed about the periphery thereof, the jaws of each pair being relatively movable to grip the blank and the pairs being movable simultaneously and as a unit in a direction parallel to the axis of said block to draw the blank into tight engagement with the block, a second block adapted to cooperate with the first, means for heating the blocks, and power-driven means for giving the blocks a relative movement into and out of cooperating relation.

3. A machine for finishing hats which comprises the combination of a block adapted to receive a hat blank, means associated therewith and operable to engage the edges of the blank and movable in a direction parallel to the axis of said block to draw the blank into tight engagement with the block, a second block movable into cooperating relation with the first, power-driven means for effecting the movement of the second block relative to the

first, and individual heating means for the blocks.

4. In a machine for finishing hats, the combination of a block adapted to receive a hat blank, a plurality of gripping devices disposed about the periphery of the block, means for operating the devices to cause them to grip the blank, the said means thereafter operating to move the devices as a unit to draw the blank into tight engagement with the block, and means for rotating the block and gripping devices while the blank is held tightly thereon by said gripping devices.

5. In a machine for finishing hats, the combination of a block adapted to receive a hat blank, a rotary shaft on which the block is mounted, a plurality of gripping devices mounted on said shaft to rotate therewith and projecting beyond the periphery of the block, means for rendering the gripping devices effective to grasp the edge of the blank placed on the block, said means also being operative to move the gripping devices as a unit to draw the blank into tight engagement with the block, means for rotating said shaft, and a tool operable to perform work on said blank as the block is rotated.

6. In a machine for finishing hats, the combination of a block adapted to receive a hat blank, a shaft on which the block is mounted, a plurality of gripping devices associated with the block at the periphery thereof and mounted on the shaft for rotation therewith, means for moving the gripping devices to effect engagement with the edges of the blank and for moving the devices as a unit to draw the blank into tight engagement with the block, means for locking the gripping devices in effective position, a motor for rotating the shaft, and a tool for operating on the surface of the blank as the latter is rotated with the block.

7. In a machine for finishing hats, the combination of a block adapted to receive a hat blank, a shaft on which the block is mounted, a collar slidable on the shaft but rotatable thereby, a plurality of gripping devices mounted on the collar, stationary means on the shaft for engaging certain of said gripping devices, the movement of the slidable collar rendering the gripping devices effective to grasp the edges of the hat blank and to draw the blank into tight engagement with the block, a motor for rotating the shaft, and a tool for operating on the blank as it is rotated with the block.

8. In a machine for finishing hats, the combination of a block adapted to receive and support a hat blank, said block engaging substantially the entire inner surface of the blank, the said block being of non-circular cross-section, means for rotating the block, a tool for operating on the outer surface of the portion of the blank supported on the block, and means rotatable with the block for mov-

ing the tool relative to the axis of rotation of the block to insure that the tool may operate with uniform action on the blank.

9. A machine for finishing hats, which comprises the combination of a block adapted to receive a hat blank, a second block adapted to cooperate therewith, a mounting for said second block movable toward and away from said first block, a motor for effecting the movement of the second block, and stop mechanism for shutting down said motor when the second block reaches the desired limit of travel toward and away from said first block.

10. A machine for finishing hats, which comprises the combination of a block adapted to receive a hat blank, a second block arranged to cooperate with the first, a carriage for the second block, a resilient mounting for said block on said carriage, guideways for said carriage in its movement toward and away from said first block, a motor for moving said carriage toward and away from said first block, and limit switches at each end of the path of travel of the carriage engageable thereby to stop the motor when the carriage has moved to the desired limit of travel in either direction.

11. A machine for finishing hats, which comprises the combination of a table, a shaft projecting through an opening in the table, a block mounted on the shaft above the table and adapted to receive a hat blank, vertical guideways above the block, a carriage movable in the guideways, a block mounted on the carriage and movable thereby into and out of cooperating relation with the first block, power means for moving the carriage in both directions, and automatic means for stopping the carriage at the desired limit of travel in either direction.

12. A machine for finishing hats, which comprises the combination of a table, a shaft projecting through an opening in the table, a block mounted on the shaft and adapted to receive a hat blank, a plurality of gripping devices disposed about the periphery of said block, means movable lengthwise of the shaft to cause the gripping devices to grip the edge of a blank placed on the block and to move said device in a direction parallel to the axis of the shaft to draw this blank into tight engagement with the block, the said means being operable through the opening in the table, a treadle for operating said means, and means for locking said treadle in a position to hold said gripping devices in effective position.

13. A machine for finishing hats, which comprises the combination of a table, a shaft mounted vertically to extend through an opening in the top of said table, a block mounted on the shaft above the table and adapted to receive a hat blank, gripping devices disposed about the periphery of the block, means operable through the opening

- in said table to cause said gripping devices to grip the edges of the blank and to move said devices in a direction parallel to the axis of the shaft to draw said blank into tight engagement with the block, guideways disposed above the block, a second block adapted to cooperate with the first mounted in said guideways and movable toward and away from said first block, means for rotating said shaft and devices, a carriage on the top of the table movable toward and away from the first block, and means mounted on said carriage for performing a finishing operation on the blank in place on the first block.
14. In a hat finishing machine, the combination of a block, a plurality of gripping devices around the block adapted to grip the edge of a blank in place on the block, and means for causing the devices to grip said blank and to move in a direction parallel to the axis of the block to stretch the blank on the block.
15. In a hat finishing machine, the combination of a block, a shaft on which the block is mounted, a plurality of gripping devices mounted on the shaft at one side of the block and having co-operating gripping parts adapted to grip the edge of a blank in place on the block, and means for causing the said parts to grip the blank and for moving the devices parallel to the shaft to stretch the blank on the block.
16. In a hat finishing machine, the combination of a block, a shaft on which the block is mounted, a plurality of gripping devices mounted on the shaft at one side of the block and having co-operating gripping parts adapted to grip the edge of a blank in place on the block, means for causing the said parts to grip the blank and for moving the devices parallel to the shaft to stretch the blank on the block, and means for rotating the shaft, the block and devices moving with it.
17. In a hat finishing machine, a block, a vertical shaft on which the block is mounted, a plurality of gripping devices mounted on the shaft below the block and having co-operating jaws extending beyond the edge of the block, and means for operating the devices to cause the jaws to grip the edge of a blank on the block and to move the devices parallel to the shaft to stretch the blank on the block.
18. In a machine for finishing hats, the combination of a block adapted to receive a hat blank, a shaft on which the block is mounted, a plurality of gripping devices having co-operating jaws arranged to grip the edge of a blank in place on the block, means for operating the devices to cause the jaws to grip the edge of the blank on the block and to move the devices in a direction parallel to the axis of the block to stretch the blank, means for rotating the block and the

group of gripping devices, and a tool having a traveling operating surface for acting on the outer surface of the blank on the block.

19. In a hat finishing machine, a block for receiving and supporting a hat blank, gripping devices for stretching the blank over the block, means for rotating the block and the devices while the latter grip the blank, and a tool having a traveling working surface adapted to operate on the exterior of the blank in place on the block.

20. In a hat finishing machine, a non-circular block adapted to receive and support a hat blank, means for drawing the blank over the block and holding it taut thereon, means for rotating the block and the said drawing means, a tool having a traveling operating surface adapted to operate on the surface of the blank in place on the block, and means for moving the tool toward and away from the block as the latter rotates.

In testimony whereof I affix my signature.
LOUIS PLATT.
